REINFORCING BAR

Joseph D. Stites, Onancock, Va.

Application March 29, 1940, Serial No. 326,616

4 Claims. (Cl. 72—111)

This invention relates to a reinforcing bar, and more particularly to a twisted reinforcing bar for use in reinforcing concrete.

An object of this invention is to provide an improved solid, twisted reinforcing bar.

Another object of this invention is to provide a solid twisted reinforcing bar having a relatively high yield point and relatively low fiber stress.

Still another object of this invention is to provide a twisted reinforcing bar having a large effective bond area.

An additional object of this invention is to form a reinforcing bar having an extremely high compression strength.

A further object of this invention is to provide a solid twisted reinforcing bar having such a cross-section that after the bar is twisted to obtain a predetermined yield point there will be less stress on the outer fibers, as compared with ordinary bars of equal cross-sectional area given the same amount of twist.

A still further object of this invention is to provide a solid twisted reinforcing bar having all of the advantages and none of the disadvantages of similar bars formed by the twisting together of two independent bars.

Other objects will be in part obvious from the annexed drawing and in part indicated in connection therewith by the following analysis of this invention.

This invention accordingly consists in the feature of construction, combination of parts and in the unique relation of the members and the relative proportioning and disposition thereof, all as more completely outlined herein.

To enable others skilled in this art so fully to comprehend the underlying features thereof that they may embody the same by the numerous modifications in structure and relation contemplated by this invention, a drawing depicting a preferred form has been annexed to part of this disclosure, and in such drawing:

Fig. 1 is a plan view of a bar, formed in accordance with this invention, before twist;

Fig. 2 is the same bar shown in Fig. 1 after it has been twisted;

Fig. 3 is a cross-sectional view along the line III—III of Fig. 1;

Fig. 4 is a cross-sectional view along the line IV—IV of Fig. 2.

Figs. 1 and 3 illustrate a preferred shape of bar to be used in the present invention, before it is twisted. It is readily seen that this solid bar is formed of two outer circular sections 1 and 3 integrally interconnected together by a web or 55

intermediate portion 2. Such a bar may be formed or shaped by any suitable method known to those skilled in the art, such as hot or cold rolling, drawing or any other method. The bar 5 is then simultaneously twisted and stretched by clamping the ends 5 and 6 and twisting one end relatively to the other. This twisting and stretching is carried out until a substantial portion of the circular sections 1 and 3 are stressed 10 beyond their elastic limit. It is important for the purposes of this invention that during the twisting operation the ends of the bar be fixed relatively to one another in the longitudinal direction, so that during the twisting operating 15 there will be no shortening of the bar and accordingly no change in the transverse cross-sectional area. After the bar has been twisted, its central section 7 between the clamped end portions 5 and 6 will have a shape substantially 20 as shown in Fig. 2.

As stated above, the effective transverse cross-sectional area of the twisted bar will be the same as that of the bar before twisting, despite the fact that there will be a lengthening of the individual circular members making up the bar. This will be apparent from a study of Figs. 3 and 25 4. Fig. 4 illustrates the circular cross-sectional area of the bar after twisting which will be seen to be the same as Fig. 3. Since during the twisting operation the bar as a whole is not permitted to shorten and therefore there will be the same amount of material between the fixed ends, the actual effective cross-sectional area of the entire bar will be exactly the same as before the twisting 30 operation.

In order to increase the bond and prevent slip between the reinforcement bar and the concrete, the former may be provided with one or more ribs, such as indicated at 4. It will be seen that any 40 deformation in the bar can be used for this purpose. The provision of transverse ribs 4, interconnecting the bars and webs, also serves to prevent rupture between the bars and web during the twisting operation, and thus permits the use 45 of a relatively small web and the positioning of a relatively larger amount of material remote from the axis of twist.

It will be obvious to those skilled in this art that the invention is not limited to the form of 50 bar illustrated by way of example, but comprehends any type of bar in which large masses of material are uniformly spaced about and relatively to the axis of the bar itself, which in in this case is the twisting axis, these masses being interconnected by a smaller amount of material.

lying in the axis. In other words, the type of bar contemplated is one which has a large amount of inertia about its central longitudinal axis, as compared with known bars of the same cross-sectional area. Instead of using two portions connected with another, a plurality of such portions, such as three or four can be used, and these portions need not be circular in shape, but may have any uniform cross-sectional shape.

The invention described above, will be seen to adequately fulfill the objects primarily stated. As compared with reinforcing bars consisting of two bars twisted and stretched together, the bar formed in accordance with the present invention will have more effective bond surface, a higher modulus of elasticity and a higher compression value. As compared with a single twisted bar of simple square or circular cross-section, the present bar will permit the attainment of a high yield point with less actual stress upon the fibers of the bar. This results from the fact that the yield point of the entire bar is the average result of cold working the bar over its entire cross-sectional area. Since in the type of bar proposed by the present invention a greater amount of material will be twisted compared to the round or square bar, as there is relatively more material spaced at a greater distance from the twisting axis, it follows that with lower actual stresses on the outer fibers of the material the same yield point for the bar as a whole may be attained. The shape of the bar of the present invention also gives it a greater strength in compression than the usual single solid bar.

It is contemplated that the bar of the present invention will be made of the usual "intermediate grade" reinforcing steel, although it is obviously not limited to fabrication by this material alone, but may be used with any suitable steels or alloys.

The stresses set up in the bar of the present invention are well within the breaking point of the outer fibers, and additional cold working such as bending can be done without reaching the breaking point.

Since a bar of the character of this invention has the stiffness of an I beam section, it will be stronger than the ordinary single bar or the bar formed by the twisting together of two independent bars. This increased stiffness permits it to be laid in forms without sagging, while the irregularity of its surface permits it to be tied without slipping.

Having described an illustrative embodiment of

the invention, it is accordingly pointed out that various changes and modifications therein are contemplated, without departing from the invention as set forth in the following claims.

5 I claim:

1. A twisted reinforcement bar, comprising two portions of substantially the same cross-sectional area integrally interconnected by a web of lesser cross-sectional area than either individual portion, said portions and web being twisted as a unit about the longitudinal axis of the bar, and longitudinally spaced, relatively narrow transversely extending ribs interconnecting said portions and said web.

10 15 2. A twisted reinforcement bar comprising two cylindrical portions of substantially the same cross-sectional area integrally interconnected by a web of a lesser cross-sectional area than either portion, said two portions and web being twisted as a unit about the longitudinal axis of the bar, and longitudinally spaced, relatively narrow transversely extending ribs interconnecting said portions and said web.

20 25 3. A reinforcement bar comprising a plurality of portions of substantially the same cross-sectional area equally spaced from and about a common longitudinal axis, means extending along and including said axis for integrally interconnecting said portions, said means having a lesser cross-section than any of said portions, said portions and connecting means being twisted about said axis as a unit to form a single solid twisted bar, and longitudinally spaced, relatively narrow transversely extending ribs interconnecting said portions and said connecting means.

30 35 4. A reinforcing member comprising a plurality of longitudinally extending metal bars whose adjacent longitudinal sides are integrally interconnected by a relatively narrow web, the transverse

40 45 40 cross-section of the whole reinforcing member being such that more than half of the metal of each bar is spaced at a greater distance from the longitudinal axis of the member, extending through the center of the web, than the radius of corresponding circular bars having the same total cross-sectional area as that of the whole reinforcing member, said bars being twisted about

40 45 45 said axis to form a twisted reinforcing member, and longitudinally spaced, relatively narrow transverse ribs interconnecting said bars and said web to prevent rupture between said bars and said web during twisting.

JOSEPH D. STITES.

CERTIFICATE OF CORRECTION.

Patent No. 2,256,060.

September 16, 1941.

JOSEPH D. STITES.

It is hereby certified that error appears in the printed specification of the above numbered patent requiring correction as follows: Page 2, first column, line 2, for "amount" read --moment--; and that the said Letters Patent should be read with this correction therein that the same may conform to the record of the case in the Patent Office.

Signed and sealed this 24th day of March, A. D. 1942.
